UNITED STATES PATENT OFFICE.

ERIK S. PALMER, OF NEW HAVEN, CONNECTICUT, ASSIGNOR TO WINCHESTER REPEATING ARMS CO., OF NEW HAVEN, CONNECTICUT, A CORPORATION.

LUMINOUS SIGHT FOR FIREARMS.

1,307,063.

Specification of Letters Patent. Patented June 17, 1919.

Application filed January 24, 1919. Serial No. 272,836.

To all whom it may concern:

Be it known that I, ERIK S. PALMER, a citizen of the United States, residing at New Haven, in the county of New Haven and Haven, State of Connecticut, have invented a new and useful Improvement in Luminous Sights for Firearms; and I do hereby declare the following, when taken in connection with the accompanying drawings and the characters of reference marked thereon, to be a full, clear, and exact description of the same, and which said drawings constitute part of this application, and represent, in—

Figure 1 a perspective view of my improved luminous rear sight.

Fig. 2 a broken view thereof in vertical section on the line 2—2 of Fig. 1.

Fig. 3 a perspective view of my improved luminous front sight.

Fig. 4 an enlarged view thereof, in central vertical section on the line 4—4 of Fig. 3.

My invention relates to improved luminous sights for firearms, whereby greater accuracy of aimed fire is secured in poor light or at night, the object being to produce at a low cost for manufacture, a simple, durable and reliable sight constructed with particular reference to facility of adaptation to individual arms.

With these ends in view, my invention consists in front and rear sights formed with vertical slots or recesses for the reception of the luminous composition and adapted at their upper ends to be filed off, if required, to adapt them to the individual arms to which they may be applied.

For the illustration of my invention, I have shown it as applied to rear and front sights of standard form. The standard rear sight shown is made in one piece and comprises a relatively long spring base 5 provided under the under face of its forward end with a dovetail fastening-rib 6 and formed at its rear end with the usual longitudinal slot 8 for the reception of an elevator which is not shown. At its extreme rear end the base 5 has an upstanding sight-leaf 9 having the usual centrally located sight-notch 10. On the rear face of the leaf 9 and on either side of the sight-notch 10, I form a vertical slot or recess 11 in each of which I place a vertical strip 12 of a luminous composition which may be of any desired character, as for instance, the composition commercially known as radiolite a sufficient

amount of which may be introduced into these recesses to give the maximum luminosity required. In these recesses the radiolite is protected from abrasion or disruption, which is highly important. By virtue of 60 locating the luminous composition in such vertical slots, I am enabled to initially construct the sight with a sight-leaf high enough for the minimum range. Now if on the trial of a given gun, after the rear sight 65 has been applied to it, the gun shoots too high, it is an easy matter for the user to file down the top of the leaf until the sight has been in this way, perhaps by repeated filings, adapted to the individual gun. The 70 point to be noted is, that the filing down of the flat upper edge of the leaf 7 shortens the vertical slots 11 without changing their character. The filing down of the flat upper edge of the leaf 7 affects the proportionate 75 removal of the luminous material 12 and the proportionate lowering of the sight notch 10 so that the upper edges of the luminous material, constituting the night-aiming points, and the sight-notch, constituting day-aiming 80 point, are moved downward to the same extent to adapt the sight to the individual gun. This result proceeds from the fact that the luminous material is located in vertical 85 slots of uniform width.

The standard front sight herein shown, consists of a transversely arranged dovetail-rib 13 or fastening-member from which the sight-leaf 14 rises at a right angle to the axis thereof, the rear edge of this leaf being 90 formed with a vertical slot or recess 15 for the reception and protection of a strip-like body 16 of radiolite or other luminous composition. The leaf 14 is initially made high enough to adapt it to have its upper edge 95 filed down to meet the shooting requirements of the particular gun to which it may be applied. Here again the filing off of the top of the leaf in no wise changes the character or operation of the sight but simply adapts 100 it to a given gun.

It is obvious that sights other than those of the particular forms shown and described, may have my invention applied to them, my invention being characterized not by 105 the structure of the sights, but by their provision with vertically arranged slots or recesses for the reception and protection of the luminous material and the adaptation of the parts in which these slots or recesses are 110

located to have their upper edges filed away to adapt the sights to the individual guns to which they may be applied.

I claim:—

- 5 1. A gun-sight formed with a vertical slot or recess for the reception and protection of luminous material and adapted to have its upper edge filed away with the proportionate removal of the luminous material, where-
10 by the night-aiming point is changed by the same amount as the day-aiming point to adapt the sight to the individual gun.
- 15 2. A gun-sight having a plurality of vertical slots or recesses for the reception and protection of luminous material and adapted to have the upper edge of the part containing such slots or recesses filed away with the proportionate removal of the luminous material, whereby the night-aiming point is
20 changed by the same amount as the day-aiming point to adapt the sight to the individual gun.
- 25 3. A rear sight for firearms, the said sight having a base formed at its rear end with an upstanding sight-leaf the rear face of which is formed with two vertical slots located on opposite sides of the sight-notch, for the re-

ception and protection of luminous material, the upper edge of the leaf being adapted to be filed away with the proportionate removal of the luminous material, whereby the night-aiming point is changed by the same amount as the day-aiming point to adapt the sight to the individual gun.

4. A front sight for firearms, consisting of a transverse fastening member and an up-
30 standing leaf located at a right angle thereto and having its rear edge formed with a vertical slot or recess for the reception and protection of luminous material and having its upper edge adapted to be filed away with the proportionate removal of the luminous material, whereby the night-aiming point is
35 changed by the same amount as the day-aiming point to adapt the sight to the individual gun.

In testimony whereof, I have signed this specification in the presence of two sub-
40 signing witnesses.

ERIK S. PALMER.
